BOAT HULL

James W. Greig, Grosse Pointe Park, and Leslie J. Ber-
ridge, Detroit, Mich., assignors to Woodall Industries,
Incorporated, Detroit, Mich., a corporation of Mich-
igan

Filed Jan. 16, 1963, Ser. No. 73,190

Term of patent 14 years

(Cl. D71—1)

FIG. 3

FIG. 4

FIG. 1 is a perspective of a boat hull showing our new design;

FIG. 2 is a side elevation of a boat hull shown in FIG. 1;

FIG. 3 is a plan view of the boat hull shown in FIG. 1;

FIG. 4 is a bottom view of the boat hull shown in FIG. 1;

FIG. 5 is a front elevation of the boat hull shown in FIG. 1;

FIG. 6 is a rear end elevation of the boat hull shown in FIG. 1;

FIG. 7 is a cross sectional view taken on the line 7—7 of FIG. 3;

FIG. 8 is a cross sectional view taken on the line 8—8 of FIG. 3.

We claim:

The ornamental design for a boat hull, substantially as shown.
